CLAIM

The ornamental design for a handheld device, as shown and described.

DESCRIPTION

FIG. 1 is a bottom, front, right perspective view of a handheld device showing my new design;

FIG. 2 is a bottom, rear, left perspective view thereof;

FIG. 3 is front elevation view thereof;

FIG. 4 is a rear elevation view thereof;

FIG. 5 is a right side view thereof;

FIG. 6 is a left side view thereof;

FIG. 7 is a top plan view thereof; and,

FIG. 8 is a bottom plan view thereof.

The broken lines shown in the drawings illustrate positions of the handheld device that form no part of the claimed design.
